DRIP DEFLECTOR

Walter M. Bates, Jr., Penns Grove, N. J.

Application August 24, 1951, Serial No. 243,465

1 Claim. (Cl. 20—70)

This invention relates to a drip deflector and more particularly to a deflector of corrosion resisting material adapted to be attached to a window sill to deflect rainwater away from a building wall below the window sill and thus reduce staining of the building wall.

It is among the objects of the invention to provide an improved drip deflector which extends outwardly of the outer edge and across the ends of an associated window sill and receives rainwater from an adjacent window and deflects the water outwardly from the building wall below the window sill to prevent the water from staining the outer surface of the building wall; which can be mounted on an existing window sill with no material modification of the window construction and is adjustable for window sills of different lengths; which is formed of corrosion and weather resisting material; which is easy to apply and does not detract from the appearance of a building to which the drip deflector is applied; and which is simple and durable in construction, economical to manufacture, and effective in operation.

Other objects and advantages will become apparent from a consideration of the following description and the appended claim in conjunction with the accompanying drawing wherein:

Figure 1 is a perspective view of the lower portion of a window with a window sill extension illustrative of the invention applied to the window sill; and

Figure 2 is a perspective view of the window sill extension.

With continued reference to the drawing, the window fragmentarily illustrated in Figure 1 has a window sill 10 extending along its bottom end and projecting outwardly somewhat beyond the outer surface of the associated building wall, not illustrated, in a manner well known to the art, and has external trim side members or stiles 11 and 12 of substantially rectangular cross sectional shape extending perpendicularly upwardly from the window sill 10 at the respectively opposite ends of the latter.

The drip guard or deflector indicated at 13, is a sheet metal structure, preferably formed of a corrosion resisting metal, such as, galvanized iron or aluminum, and includes an intermediate portion 14 of elongated rectangular shape and end portions or guards 15 and 16 extending perpendicularly from the same side of the intermediate portion at the respectively opposite ends of the latter.

The intermediate portion 14 has along one longitudinally extending edge an attaching strip 17 which is provided with nail holes 18 at spaced apart locations therealong. The attaching strip 17 is inclined transversely relative to the intermediate portion 14, so that when the marginal portion or attaching strip 17 is nailed to the substantially horizontal under surface of a window sill adjacent the outer edge of the latter, the remaining portion or flange 19 projects outwardly and downwardly beyond the outer edge of the window sill.

The end portions or guards 15 and 16 have straight bottom edges substantially in the plane 15 of the upper surface of the attaching strip 17, and have a width greater than the combined width of the strip 17 and the flange 19 the major portions of said guards extending beyond the said attaching strip 17.

20 The edges 20 and 21 of the end portions of guards 15 and 16 remote from the flange 19 are substantially perpendicular to the edges 22 and 23 which lie in the plane of the attaching strip 17, and the edges 24 and 25 of the end portions 25 or guards 15 and 16 opposite the edges 22 and 23 lie substantially parallel to the edges 20 and 21. The edges 26 and 27 extend upwardly and inwardly as they recede from the junctions of the lower edges of the guards with the outer edge of the flange 19, and carried by the guards adjacent the top edges 24 and 25 thereof are outwardly and upwardly inclined flanges 24' and 25' respectively. Nail holes, as indicated at 28 for the end member or guard 15, and 29 for the end member 16, are provided in the end members or guards adjacent the top edges 24 and 25 thereof, these nail holes being spaced apart a distance less than the thickness of the outside trim members or stiles 11 and 12 of the window frame.

30 35 The attaching strip 17 and the flange comprising the intermediate portion 14 of the drip deflector is preferably provided in a length corresponding to the maximum length of the window sill to which the device is to be applied and is divided intermediate its length along a line extending transversely thereof, so that the adjacent ends of the two parts of the intermediate portion 14 can be overlapped, as illustrated in Figure 1, when the deflector is applied to a window sill of less than the maximum length to thereby accommodate the deflector to window sills of different lengths.

40 45 50 In applying the deflector to a window sill, one part of the intermediate portion 14 is placed

under the window sill with the associated end member or guard against the corresponding end of the window sill and with the inner edge of the strip 17 extending along the outer bottom edge of the window sill, nails are driven through the holes 18 and upwardly into the window sill and nails are driven through the holes 29 and into the corresponding side trim member or stile to rigidly secure this part of the deflector to the window sill. The other part of the deflector is then placed on the window sill in the same manner with the parts of the intermediate portion 14 of the extension overlapping at their adjacent ends, if necessary, and nails are driven through the nail holes in this second part of the extension to secure the latter firmly to the window sill and the corresponding side trim member or stile.

When the drip deflector is in place, rain-water flowing down the outer edges of the stiles 20 will encounter the flanges 24' and 25' and will be directed thereby onto the flange 19, and water flowing down the window will be confined between the guards 15 and 16 and caused to flow onto the flange 19. Water flowing off of the sill 10 will also flow onto the flange 19 and all of the water will be deflected over the outer edge of the deflector and will fall from there to the ground without contacting the side wall of the building below the associated window.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A drip deflector for attachment to a window frame comprising an elongated rectangular attaching strip adapted to be attached to the under side of the window sill of a window frame, an elongated rectangular drip deflecting flange carried by the attaching strip and projecting outwardly and downwardly from one longitudinal side edge thereof and beyond the outer side of the window sill, guards carried by the flange adjacent opposite ends thereof, said guards extending upwardly and rearwardly from the flange in substantially perpendicular relation to the attaching strip for attachment to the stiles of the window frame above the sill thereof, said guards overlying opposite ends of the window sill, and flanges carried by the guards and extending upwardly and outwardly therefrom to form with the stiles gutters which receive water running down the stiles and direct it onto the drip deflecting flange.
